ELECTRICAL NERVE STIMULATOR

Blair A. Rowley and Ross D. Young, Columbia, Mo.,
assignors to Institute of Bioengineering Research In-
corporated

Filed Feb. 12, 1970, Ser. No. 21,406

Term of patent 14 years

Int. Cl. D24—02

U.S. Cl. D83—1

FIG. 2

FIG. 1

FIG. 1 is a front elevation of a nerve stimulator showing our new design;

FIG. 2 is a bottom plan view as seen in the direction of line 2—2 of FIG. 1;

FIG. 3 is a top plan view; and

FIG. 4 is an elevation as seen from the right of FIG. 1.
We claim:

The ornamental design for an electrical nerve stimulator, substantially as shown.
